WILLIAM H. DURKEE, OF CLEVELAND, OHIO, ASSIGNOR OF ONE-HALF TO B. O. HULL,
OF BURTON, OHIO.

DEVICE FOR FITTING DOORS.

1,257,200.

Specification of Letters Patent. Patented Feb. 19, 1918.

Application filed March 2, 1917. Serial No. 151,981.

To all whom it may concern:

Be it known that I, WILLIAM H. DURKEE, a citizen of the United States, residing at Cleveland, in the county of Cuyahoga and 5 State of Ohio, have invented certain new and useful Improvements in Devices for Fitting Doors, of which the following is a specification.

This invention relates to a pattern or template device used for fitting doors or other objects within frames or openings, and the main object of the invention is to provide a device for the purpose set forth, that is universally adjustable, or that can be readily 10 adjusted within the frame or opening to fit or conform to the contour of said opening and thereby serve as a pattern or template which may be placed on the door or other object to be fitted, the exact contour of the 15 opening can then be traced on the object and said object cut accordingly, thereby greatly facilitating the operation of fitting the object to the opening.

Heretofore the fitting of doors to old frames which for various reasons have become distorted or out of square or plumb, has been a matter of annoyance, a great deal of time and labor being necessarily occupied in the taking of various measurements and 20 angles and transferring them to the door to be fitted. The liability of errors in transferring the measurements and numerous other objectionable features common to the old method of fitting are familiar to those versed 25 in the art.

As far as I know, the devices at present employed for fitting doors are vertically and horizontally adjustable the corners being right angular and rigid. These devices are 30 more or less convenient for new work where the frames are supposed to be true and plumb. While the improved device is serviceable and highly efficient for fitting doors and the like in frames on new work, it is also 35 particularly adaptable and convenient on repair work owing to the relative adjustability of the several members whereby not only the vertical and horizontal alinements or dimensions are obtainable, but also the corner angles, other than right angles, are readily 40 formed by the simple manipulation of the parts, thereby making the device equally adaptable for fitting doors to distorted frames and to true or rectangular frames.

The construction of the device with its simple and universal adjustments provides a time and labor saving instrument that is economical, durable and efficient.

With the above mentioned and other apparent objects in view the invention consists 55 in the construction, arrangement and combination of the elements as described in the following specification and pointed out definitely in the annexed claims, reference being made to the accompanying drawings in 60 which similar characters of reference are used to designate similar parts, and in which Figure 1 illustrates the improved device fitted within a true or rectangular frame.

Fig. 2 illustrates the device as adjusted to 70 fit, and as removed from a distorted door frame.

Fig. 3 illustrates the device adjusted to its extreme vertical, right angle adjustment, portions of the device being broken away for 75 convenience in arrangement of drawing.

Fig. 4 illustrates the device adjusted to the extreme horizontal, right angle adjustment with portions broken away for the same reason as above mentioned.

Fig. 5 is a section on line 5—5 of Fig. 1.

Fig. 6 is a section on line 6—6 of Fig. 4.

Fig. 7 is a detail on an enlarged scale of a certain type of adjusting means that may be used.

In the embodiment of the invention as illustrated in the accompanying drawings, the device is composed of two side members 1 and 2, two end members 3 and 4, an intermediate supporting member 5, and a series of 90 connecting members 6, 7, 8, 9, 10, 11, 12, and 13.

In a preferred construction the members 1, 2, 3, and 4 are light L bars, the member 5 is of wood, and the connecting members are 95 flat metal parts, but it will be understood that any suitable material may be used for the several elements without departing from the spirit of the invention.

The connecting members 6 and 7 are provided, respectively, with slots 6^a and 7^a and are pivotally attached to the end member 3 by screws 3^a, and are connected with the member 5 by a screw 5^a passing through the slots 6^a and 7^a and threaded into member 5. 100 The connecting members 12 and 13 are likewise provided with slots 12^a and 13^a and are pivotally attached to the end member 4 by

screws 4^a and connected with member 5 by a screw 5^b passing through the slots 12^a and 13^a and threaded into member 5.

Connecting members 8 and 10 are pivotally connected with the side alinement member 1 by screws 1^a and 1^b, and connecting members 9 and 11 are likewise connected with the side alinement member 2 by screws 2^a and 2^b. The members 8, 9, 10, and 11 are provided, respectively, with slots 8^a, 9^a, 10^a, and 11^a, and are connected with the supporting member 5 by screws 5^c and 5^d. The members 8 and 9 overlap as shown and the screw 5^c passes through the slots 8^a and 9^a and is threaded into the member 5, while the members 10 and 11 are similarly connected with member 5 by the screw 5^d.

It will readily be understood from the foregoing description that by loosening all of the screw members the device may be accommodated to the contour of the interior of a frame or opening, and when thus adjusted and the screws tightened, the device as a whole becomes rigid and can be removed from the opening and used as a templet for cutting the object to be fitted to the opening.

In Fig. 2 the device is illustrated as adjusted to the contour of a distorted door frame. While this may show an exaggerated condition it serves to illustrate the functions, as it will be seen that by placing the device as adjusted and rigidly fixed by the set screws, on the face of a door and tracing on the outer lines *a*, *b*, *c*, and *d* the angles *w*, *x*, *y*, and *z* are accurately transcribed without the employment of other tools.

The device admits of vertical, horizontal, and angular adjustments, or in other words, it is universally adjustable.

Bolts 20 provided with wing nuts 21 may be used in place of the set screws shown in the several figures, and the same results obtained, the parts being held in adjustment by the bolts passing through the several elements and being held rigid by the wing nuts.

It will be seen that all the screws may be loosened and the device adjusted to a compact assemblage for storage or transportation. While I have shown and described a practical embodiment of the invention, it will be understood that I am not confined

to this construction specifically, as there may be changes in design, relative proportions of parts, and various other minor details of construction without departure from the nature of the invention, the limitations being governed by the scope of the following claims.

What I claim and desire to secure by Letters Patent is.

1. A pattern device for fitting objects to openings, comprising side and end alinement members directly detached from each other, an intermediate member, and pivotal and slidale means connecting said alinement members with the intermediate member, whereby the alinement members may be adjusted to the sides and ends of the opening and to obtuse, acute, or right angular relation of said ends to the sides.

2. In a pattern device for fitting objects to openings, the combination of two side members; two end members; an intermediate supporting member; connecting members pivotally connected with the end members and adjustably connected with the supporting member; connecting members pivotally connected with the side members and adjustably connected with the supporting member, whereby said side and end members are relatively adjustable vertically, horizontally and angularly.

3. In a pattern device for fitting objects to openings the combination of two side members; two end members; an intermediate supporting member; connecting members pivotally connected with the end members and adjustably connected with the supporting member; connecting members pivotally connected with the side members and adjustably connected with the supporting member, whereby said side and end members are relatively adjustable vertically, horizontally and angularly; and means for making all connections rigid after adjustment.

In testimony whereof I affix my signature in the presence of two witnesses.

WILLIAM H. DURKEE.

Witnesses:
